UNITED STATES PATENT OFFICE.

WILLIAM CAMERON, OF CHICAGO, ILLINOIS, ASSIGNOR TO TORRIS WOLD & COMPANY,
OF CHICAGO, ILLINOIS, A CORPORATION OF ILLINOIS.

METHOD OF SEALING CANS.

1,192,605.

Specification of Letters Patent. Patented July 25, 1916.

Application filed August 26, 1914. Serial No. 853,585.

To all whom it may concern:

Be it known that I, WILLIAM CAMERON, a citizen of the United States, and resident of Chicago, in the county of Cook and State 5 of Illinois, have invented certain new and useful Improvements in Methods of Sealing Cans, of which the following is a specification.

The present invention has to do with the 10 art of can making and sealing and is particularly concerned with the capping of cans in order to provide a proper sanitary joint for the same.

In the general practice of the art it has 15 been customary to apply the sealing compound to the marginal portions of the cap within the groove formed by the upset flange which co-operates with the flange of the can body in the seaming operation. This application, however, of the sealing compound 20 has proven objectionable in that during the uniting of the cap to the body it has been possible for the sealing compound to pass into the interior of the body from the cap 25 groove and into contact with the contents thereof, with a resultant deleterious effect upon such contents.

It is therefore the object of the present invention to provide a novel method for 30 sealing cans through the medium of which a thoroughly sanitary joint is obtained between the can body and its cap and by means of which entrance of the sealing compound into the can body is wholly avoided.

Other objects and advantages of the invention will be seen as the nature of the improvements is better understood, the invention consisting in the novel method hereafter fully described, illustrated in the accompanying drawings and finally pointed 35 out in the claims.

In the drawings: Figure 1 is a side elevation of a preferred form of apparatus for carrying the present invention into effect. 40 Fig. 2 is a top plan view thereof. Fig. 3 is an end elevation of the same. Fig. 4 is a transverse sectional view on the line 4—4, Fig. 1. Figs. 5, 6 and 7 are fragmentary sectional views of a can body and its cap 45 illustrating different stages of seaming in accordance with the present invention.

Referring now in detail to the accompanying drawings, and more particularly with reference to Figs. 1 to 4 inclusive, the numeral 10 designates a trough or vat of elon-

gated form designed to receive a suitable sealing medium for providing a hermetic joint between the cap and body of a can or similar container. Arranged within the trough or vat 10 is a longitudinally disposed 60 feed roll 11, one end of which is provided with a pinion 12 which meshes with a corresponding pinion 13 carried by a stub shaft 14 arranged adjacent to the projecting end of the feed roll 11. Also carried by the 65 stub shaft 14 is a bevel gear 15 in mesh with a corresponding gear 16, which latter gear is mounted upon a transversely arranged shaft 17 operated through the medium of a sprocket pinion 18 with which 70 is associated a chain 19. The chain 19 is connected to any suitable source of power.

Rising vertically from one side of the trough or vat 11 is a pair of standards 20, each of which carries a supporting arm 21 75 adjustably connected to the standard with which it is associated, and each of said arms 21 also supports a shaft 22 upon which is mounted a pulley 23. The pulleys 23 are in alinement with each other in the direction 80 of the length of the trough or vat 10, and passing over said pulleys 23 is an endless belt 24 which constitutes a conveyer for a purpose to be presently described.

At each side of the trough or vat 10 is 85 arranged a plurality of supporting brackets 25 and connected to the brackets 25 at each side of the trough or vat is a longitudinally extending guide rail 26, said guide rails being spaced apart from each other a suitable 90 distance to accommodate the length of the cans under treatment. This width may be varied at will and to the accomplishment of this end the supporting brackets 25 at one side of the trough or vat 10 are adjustably 95 mounted, as by bolt and slot connections 27, and through the medium of this construction the distance between the rails 26 may be adjusted to suit different lengths of cans.

It is the purpose of the endless belt 24 to 100 convey the cans lengthwise of the guide rails 26, and in this movement to also impart to the cans rotation. To this end the lower run or stretch of the conveyer 24 is caused 105 to rest upon the upper portions of the can bodies, as clearly illustrated in Figs. 1, 3 and 4, while the lower portions of said bodies will travel upon a convex guide 28, which guide is mounted upon an adjustable 110 scraper-blade 29, one edge of which is ar-

ranged adjacent to the periphery of the feed roll 11. The scraper-blade 29 may be adjusted toward or away from the feed roll 11 through the medium of bolt and slot connections 30, and the purpose of this adjustment is to regulate the amount of sealing medium fed by the feed roll 11 to the flanges of the can bodies.

For imparting movement to the endless conveyer 24 the shaft 22, which is adjacent to the shaft 17 and which is arranged above the latter, is provided with a sprocket gear 31 connected by a chain 32 with a similar gear 33 mounted upon the shaft 17. Thus it will be seen that as the feed roll 11 is actuated by the shaft 17 the conveyer 24 will also be actuated in unison therewith.

The apparatus above described may be incorporated as a part of a can-making machine but its operation is not dependent upon such relation.

As before stated, it is the object of the present invention to enable the sealing of can caps upon can bodies with such a type of joint that the sealing compound or the medium employed will be precluded from entering the contents of the can at the time of the sealing operation, thereby providing a strictly sanitary joint between the cap and the body. In the use, therefore, of the present apparatus the can bodies are successively fed by a suitable chute or other means between the guide rails 26. The can bodies thus will lie between the lower stretch of the conveyer 24 and the convex guide 28 and the flanges at one end of the respective can bodies will also rest upon the feed roll 11, as clearly illustrated in Figs. 3 and 4. The feed roll 11 operating in the direction of the arrow in Fig. 4 will take up the compound or sealing medium contained within the trough or vat 10 and the scraper 29 having been properly adjusted with respect to the feed roll 11 the sealing compound or medium will pass beyond the inner edge of such scraper 29 in the form of a thin film or sheet. As the flange at one end of each of the can bodies rests upon the feed roll 11 during the traverse of the can bodies between the guide rails 26, it will be obvious that such flange will intercept the movement of the film of the sealing medium in a line which is substantially at right angles to the direction of movement of the film, and as the can bodies continue their rotation it will also be seen that the sealing medium is deposited upon the can body flange throughout the entire length of the latter. As will also be understood, this depositing of the sealing compound is upon the outer face or exterior wall of the can body flange and after the respective can bodies have passed throughout the length of the feed roll 11 the flanges thereof which have been in contact with said roll will be entirely covered with

the sealing medium at their outer faces. After the bodies are filled with the desired contents, and while the sealing compound is still in a plastic state, the caps are applied to the bodies, whereupon the caps are seamed, and thus a hermetic joint is obtained between the caps and the bodies. In Figs. 5, 6, and 7 are disclosed various stages of the assembling and seaming of the caps, Fig. 5 illustrating the position when the cap is first applied to the body. By referring to this figure it will be noted that the sealing compound 34 is deposited entirely upon that face only of the flange of the body which is a continuation of the outer face of the wall of the can body, and is next adjacent to the depending flange of the cap. In Fig. 6 the cap flange has been pressed against the body flange so that the sealing compound is interposed directly between these two flanges, and in Fig. 7 the final stage of the seaming operation is shown. In this view it is also evident that the sealing medium is wholly outside of the joint between the wall of the can and the inner wall of the groove of the cap so that entrance of the sealing compound into the interior of the can body is entirely avoided.

While the apparatus herein illustrated and described is a preferred form for carrying the present invention into effect, it will be understood that the herein described process is not wholly dependent upon this particular type of apparatus and the practice of the process therefore is not to be restricted to this particular form of apparatus.

For seaming the cap and the can body the usual type of seaming apparatus may be employed, by reason of which it is deemed unnecessary to illustrate such apparatus.

Having thus described the invention, what is claimed as new and desired to be secured by Letters Patent is:

1. The method of sealing cans, which consists in applying a sealing medium to that face only of the can body flange which is a continuation of the outer face of the wall of the can body, whereby to position the sealing medium on the exterior face only of said flange, assembling a cap on the can body with its flange overlapping the body flange, and then effecting seaming of the cap and body flanges with the sealing medium confined wholly between the marginal portions of the cap flange and said exterior face of the body flange and remote from the interior of the sealed can.

2. The method of sealing cans, which consists in applying a sealing medium to that face only of the can body flange which is a continuation of the outer face of the wall of the can body, whereby to position the sealing medium on the exterior face only of said flange, assembling a cap on the can body with its flange overlapping the body flange,

pressing the flange of the cap into engagement with said face of the body flange to which the sealing medium has been applied, and finally seaming the cap and body flanges 5 with the sealing medium confined by the seam at a point wholly outside of the joint

between the wall of the body and the inner wall of the groove of the cap.

WILLIAM CAMERON.
